By his Attorney Oscar Geier

UNITED STATES PATENT OFFICE.

GEORGE PHILIPP SCHMITT, OF NEW YORK, N. Y.

AUTOMATIC GAS-EXTINGUISHER.

1,209,890.

Specification of Letters Patent. Patented Dec. 26, 1916.

Application filed March 24, 1916. Serial No. 86,374.

To all whom it may concern:

Be it known that I, GEORGE PHILIPP SCHMITT, a citizen of the United States, and a resident of New York, in the county of 5 New York and State of New York, have invented certain new and useful Improvements in Automatic Gas-Extinguishers, of which the following is a specification.

This invention relates to improvements in 10 devices for extinguishing the flame of gas jets, particularly of the type used for heating, known as the Bunsen burners.

The principal object of the invention is to provide a means which will automatically 15 close the gas valve, when for any cause the flame becomes extinguished, thereby preventing loss of gas, and possible danger of explosion.

Another object is to provide such devices 20 in forms which may be applied to any of the ordinary type of gas burners without special difficulty and which in nowise interferes with their customary operation and use.

These and other objects are attained by 25 the novel construction and combination of parts hereinafter described and shown in the accompanying drawing, and in which:—

Figure 1 is a plan view, showing a burner having the device attached thereto. Fig. 2 30 is a side elevation of the same. Fig. 3 is a front elevation, the inlet pipe being shown in section. Fig. 4 is a fragmental edge view of the control device. Fig. 5 is a side view of the same, and Fig. 6 is a fragmental perspective view showing a detail of construction.

In the drawings, the numeral 10 represents the base of the burner, here indicated to be of the well known Bunsen type, to the 40 upper end of which is attached an inlet pipe 11, having an ordinary form of valve 12, through which gas may be supplied from any convenient source by the pipe 13.

Rising from the standard, and communicating with the pipe 11, is a vertical tube 15, the same being open at the top 16, used as a burner, and which is slotted across on one side to receive the inturned end 18 of the control element which is formed of two 50 strips of metal, respectively 19 and 20, the same being of different heat conducting properties, as for instance, brass welded or otherwise united to a corresponding strip of iron. These strips or tapes form the 55 control and are coiled spirally a few times around the open end of the burner, their

outer ends 21 extending laterally a short distance from the burner top, and having pivotally engaged with their bent ends an arm 22, formed with ratchet teeth 23 at its lower 60 side, the same passing through an elongated aperture 24 formed in the offset upper end 25 of a lever 26 pivoted on a horizontal post 27, the latter being rigidly engaged with the tube 15. 65

The lower end of the lever 26 is turned outward, forming a toe 28, adapted to receive the point 30 of a bent valve lever 32, connected to the stem 33 of the valve 12, and having affixed upon it a weight 34 of sufficient magnitude to close the valve when the lever is released from the toe 28. 70

Surrounding the post 27 is a helical coiled spring 35, one end being engaged with the burner tube 15 and the other connecting with 75 the lever 26 in such manner as to press it forward so that the toe is normally engaged with the valve lever.

In operation, the gas being turned on and the valve lever 32 held in its raised position, the heat from the gas flame causes the coil control to expand, moving the arm 22 rearwardly, causing the teeth 23 to slip through the slot 24 of the lever 26, the teeth being inoperative when moving rearward. 80 When, however, the flame becomes extinguished, the coil immediately contracts, whereupon the teeth 23 engage with the arm 25, moving the lever 26 in such manner that the toe is disconnected from the point of 85 the valve lever, allowing the valve lever 32 to drop by reason of the weight 34 and close the valve thereby cutting off the gas supply. 90

From the foregoing it will be observed 95 that a similar construction can be arranged for other forms of gas jets as well as for the Bunsen type, therefore, it is not desired to be strictly held to the exact construction shown, as modifications can be made within 100 the scope of the claims.

Having thus described my invention, what I claim as new and desire to secure by Letters Patent, is:—

1. In a device of the class described, the 105 combination with a standard, an inlet pipe connected therewith, a valve in said inlet pipe, and a vertical burner tube engaged with said standard remote from said valve, of an expansible coil passing through said 110 burner, an arm extending therefrom, a post attached to said burner tube parallel with

- said arm when the latter is in a normal position, a lever pivoted on said post, means combined with said arm adapted to actuate said lever when moving in one direction, a 5 second lever operatively engaged with the stem of said valve, a weight adjustable thereon, and means combined with said arm adapted to hold the valve lever in a raised position when in a normal position.
- 10 2. In a device of the class described, the combination with a standard, a gas supply pipe entering said standard, a valve in said gas pipe, and a vertical burner tube on said standard remote from said valve, of a plu- 15 rally coiled control comprised of two different metals engaged at the top of said burner tube having a part entered therein, an arm

formed with said control extending laterally outward, a ratchet pawl pivoted to said arm, a lever pivoted to said vertical tube, having 20 its upper end engageable with said pawl, a second lever operatively combined with said valve having a part engageable with the lower end of the first mentioned lever, means for depressing said second lever when free, 25 said means being adjustable, and means combined with the first mentioned lever for holding the valve lever in a normally open position.

Signed at New York, in the county of 30 New York, and State of New York, this 14th day of March, 1916.

GEORGE PHILIPP SCHMITT.
